UNITED STATES PATENT OFFICE

ARTHUR R. COLLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed June 4, 1924. Serial No. 717,747.

This invention relates to cash registers, and more particularly to the totalizer mechanism thereof.

The principal object of this invention is 5 to provide an adding and subtracting totalizer for use with cash registers which reduces to a minimum the amount of shift necessary between adding and subtracting positions.

10 With this and incidental objects in view, the invention comprises certain novel features of construction and combinations of parts, the essential elements of which are set forth in appended claims and a preferred 15 form or embodiment of which is herein-after described with reference to the drawings which accompany and form part of this specification.

Of said drawings:

20 Fig. 1 is a front elevation of a totalizer line with the adding and subtracting wheels mounted thereon, together with the cam for shifting the totalizer and the actuating racks for operating the totalizer wheels.

25 Fig. 2 is a side elevation of one of the adding and subtracting units, partly broken away to show one of the beveled gears and pinions which cooperate therewith.

Fig. 3 is a detail sectional view through 30 one of the pairs of adding and subtracting totalizer wheels showing the construction thereof.

Fig. 4 is a flat development of the cam previously used in machines of this type 35 to shift the adding and subtracting totalizers from one to the other of their positions.

Fig. 5 is a flat development of the cam used in the machine embodying the present 40 invention for shifting the totalizer wheels from their adding to their subtracting positions, or vice versa.

General description

45 This invention is shown embodied in a machine of the type shown and described in Letters Patent of the United States of F. L. Fuller, No. 1,242,170, granted Oct. 9, 1917, and, therefore, only such of the mechanism 50 as is considered necessary properly to show

the operation of the invention, is included in this application.

In the Fuller patent there is shown an adding and subtracting totalizer. This totalizer comprises a plurality of units, each 55 of which consists of two ordinary totalizer wheels having bevel gears fastened to their adjacent sides. There are two bevel pinions which mesh with both of the bevel gears so that the movement of one member of a pair 60 of totalizer wheels will rotate the other wheel of the pair in the opposite direction. When using a totalizer such as that just described, and as illustrated in the Fuller patent, it was necessary to shift the totalizer 65 wheels some distance to move the subtracting wheels into cooperative relation with the actuating racks when changing from the adding to the subtracting positions. This is due to the wide construction of said 70 adding and subtracting totalizer, wherein the bevel connecting gears are located between the adding wheel and the subtracting wheel.

The adding and subtracting totalizer is 75 shifted axially relatively to the actuators, to bring either the adding or the subtracting set of gears in line with the actuators, by a peripheral or drum cam, shown in Figs. 18 and 19 of said Fuller patent. But, because of 80 the location of the intermediate bevel gears between the adding and subtracting wheels of each denomination, it is necessary, in Fuller's device, to shift the adding and subtracting totalizer a greater distance axially 85 in changing from the adding to the subtracting wheels or vice versa, than it is to shift from one to another set of adding totalizers of the ordinary interspersed type.

Therefore, in order to reduce the load on 90 the machine due to the friction created by wiping an angularly arranged drum cam relatively to the shifting arm of the adding and subtracting totalizer, it has been customary to increase the length of the angular 95 portion of the drum cam, (see Fig. 4), so that the transition from the adding to the subtracting wheels of a totalizer may be effected with greater ease and without placing an abrupt load on the machine.

But as the arcuate distance through which the drum cam may be rocked is limited and defined by the number of control keys in a row on the keyboard, the increase in 5 the length of the cam to effect the shift of the totalizer from the adding to the subtracting wheels of each denomination, and vice versa, forces the elimination of keys intermediate the ends of the row of control 10 keys, (indicated in dotted lines in Fig. 4), as it would be of no avail at present to arrest the adding and subtracting totalizer in a position with its wheels intermediate the actuators.

15 The position of the totalizer is controlled from a bank of control keys, certain keys of the bank positioning the totalizer for adding, and other keys causing it to shift to its subtracting position, as is well known in 20 machines of this type. These keys control well known differential mechanism (not shown herein), which in turn positions the cams, such as shown in Fig. 4, in accordance with the key depressed. Due to the distance 25 through which it is necessary to move the totalizer wheels to shift from the adding to the subtracting position, or vice versa, it has never been practical to use more than seven credit and debit, or add and subtract 30 keys, in the control bank. If all nine keys were used as credit and debit keys, the cam groove would have to be so abrupt that the totalizer line would receive a very rapid 35 shifting movement, and, due to the friction created by such an abrupt cam, it would make the operation difficult at that point in the operation of the machine.

In the present invention, however, the distance which the totalizer line must shift, in 40 order to change from the adding to the subtracting position, has been greatly reduced, and this reduction in the movement of the totalizer line has permitted the design of a cam such as is shown in Fig. 5, the form of 45 which is such that no keys in the control bank need be omitted.

Adding and subtracting totalizer wheels

Each totalizer unit comprises an adding 50 wheel 30 and a subtracting wheel 31 (Figs. 1 and 3) adapted to be engaged with actuators 29. The adding wheel 30 is loosely mounted on a rod 32 supported by arms 33 and 34 slidable along a shaft 35 carried by 55 guide plates 36 mounted on the side frames (Fig. 1). There are as many pairs of adding and subtracting totalizer wheels in the machine as it is desired to have denominations. Each unit or pair of totalizer wheels 60 is constructed as follows: The adding wheel 30 is connected by means of a hub 37 to a bevel gear 38. Integral with the hub of the subtracting wheel 31, which is loosely mounted on the hub 37 closely adjacent the 65 adding wheel 30, is a bevel gear 39. Secured

to the rod 32 is a hub having a pair of arms 40 embracing the bevel gear 38 and extending parallel with the rod 32. Each arm 40 carries a headed stud 41 positioned radially relatively to the rod 32, which studs each 70 support a bevel pinion 42 meshing with both the adding and subtracting bevel gears 38 and 39. It can be seen from the above that when either of the adding or subtracting totalizer wheels 30 or 31 is driven, the other 75 wheel of the pair will be rotated in the opposite direction through the bevel gears 38 and 39 and the bevel pinions 42. Each of the adding and subtracting totalizer wheels 30 and 31 has a long tooth 43, the function 80 of which is very well known, and which is described in the above mentioned Fuller patent. When it is desired to subtract, the subtracting wheels 31 are engaged with the actuators 29, and are rotated forwardly or 85 clockwise (Fig. 2) thus causing the adding wheels 30 to be rotated backwardly or counter-clockwise to the same extent, thereby subtracting the desired amount from that standing on the adding wheels. 90

Shifting mechanism

As above mentioned, all the adding and subtracting totalizer wheels 30 and 31 are loosely mounted on the rod 32. This rod 95 is supported at its right hand end in the arm 33, and at its left hand end in the arm 34, both of said arms being axially slidable on the shaft 35, which is itself supported for bodily movement laterally in the guide 100 plates 36 secured to the side frames of the machine. The arm 34 has a boss 48, in which is mounted a rod 49 carrying flanged rollers 50, the lower one of which operates in a cam slot 51 (Figs. 1 and 5) formed in 105 a segmental drum cam 52 provided with a hub 53 rotatably mounted on a stud 54 supported by the left hand side frame. Upon operation of the machine, the cam 51 is differentially positioned under the control 110 of the keys in the control bank appropriate to the particular totalizer line to be operated, as set forth in the above-mentioned 115 patent to Fuller, No. 1,242,170. The conformation of the cam 52 is such that the 120 arms 33 and 34, and the rod 32 carrying the totalizer wheels, will be shifted laterally of the machine, that is towards the right from the position shown in Fig. 1; when a credit key has been depressed and the machine operated, and back again when a debit key is depressed. The parts are guided in such 125 axial shifting by a bracket 55 projecting from the side frame of the machine and having a slot 56 formed therein in which the upper roller 50 operates.

It is evident, therefore, that if a debit key is depressed, the cam 52 will position the subtracting totalizer wheels 31 in alignment with the actuators 29, and if a credit 130

key is depressed, the cam will shift the adding wheels 30 into alignment with the actuators 29. It can be seen from Fig. 1 that the totalizer wheels, as shown in that figure, 5 are positioned with the subtracting wheels 31 in alignment with the actuators, and it will be noted that only a very short movement is necessary to bring the adding wheels 30 into alignment with said actuators and 10 move the subtracting wheels out of such an alignment. As above mentioned, it is this short movement that permits the use of such a cam as that shown in Fig. 5 which enables any arrangement of a full complement 15 of nine debit and credit keys.

After the totalizer wheels have been positioned, with either the adding or subtracting wheels in alignment with the actuators 29, the totalizer wheels, rod 32, arms 20 33 and 34 and shaft 35 are moved bodily to bring the selected totalizer wheels into cooperative relation with the actuators. The means for effecting this engagement is very well known, and is described in detail in 25 the above mentioned Fuller patent, and therefore no showing or description thereof is included herein.

While the form of mechanism herein shown and described is admirably adapted 30 to fulfill the objects primarily stated, it is to be understood that it is not intended to confine the invention to the one form or embodiment herein disclosed, for it is susceptible of embodiment in various forms, 35 all coming within the scope of the claims which follow.

What is claimed is:

1. In a machine of the class described, the combination of a pair of wheels of corresponding denomination, the members of 40 which pair of wheels lie closely adjacent each other; a supporting rod for the pair of wheels and relatively to which the wheels rotate; a driving connection between the 45 wheels, including a sleeve attached to one of the wheels and projecting through the other of the wheels; a gear on the sleeve; a gear on the wheel through which the sleeve projects; a beveled pinion in mesh 50 with the gears; and means secured to the supporting rod on one side of the pair of wheels, to support the pinion.

2. In a machine of the class described, the combination of a pair of wheels of corresponding denomination, the members of 55 which pair of wheels lie closely adjacent each other; a supporting rod for the pair of wheels and relatively to which the wheels rotate; a driving connection between the 60 wheels, including a sleeve attached to one of the wheels and projecting through the other of the wheels; a gear on the sleeve; a gear on the wheel through which the sleeve projects; beveled pinions in mesh with 65 the gears; and a yoke-shaped member fast

on the rod to one side of the pair of wheels, and embracing the gears, for supporting the pinions.

3. In a machine of the class described, the combination with a supporting rod; of an adding wheel and a subtracting wheel, one of said wheels being journaled on the supporting rod and arranged closely adjacent the remaining wheel; and a driving connection between the wheels, including a sleeve journaled on the rod; the sleeve attached to that wheel which is journaled on the rod and projecting axially through said remaining wheel to form a bearing therefor; a gear on the sleeve; a companion gear on 70 said remaining wheel; and a beveled pinion meshing with the gears, so that either wheel 75 may be differentially driven by the other wheel.

4. In a machine of the class described, the combination with a supporting rod; of an adding wheel and a subtracting wheel arranged closely adjacent each other on, and differentially rotatable in either direction 80 relatively to the rod; and a driving connection between the wheels, whereby either of the wheels may be driven by the other, and including a sleeve journaled on the rod, the sleeve attached to one of the wheels and 85 projecting through the remaining wheel.

5. In a machine of the class described, the combination with a support; of an adding and a subtracting wheel arranged in substantial abutting relation and differentially rotatable relatively to the support; 90 a sleeve secured to one of the wheels and extending axially through the remaining wheel which is journaled thereon; a gear on the outer face of the said remaining wheel; an opposed gear on the outer end of 95 the sleeve; pinions connecting the opposed gears; and means to drive the gears.

6. In a machine of the class described, the combination with a support; of an adding and a subtracting wheel arranged in substantial abutting relation and differentially rotatable relatively to the support; a sleeve secured to one of the wheels and extending axially through the remaining wheel which 100 is journaled thereon; a gear on the outer face of the said remaining wheel; an opposed gear on the outer end of the sleeve; a carrier fast on the support and embracing the gear on the sleeve; pinions mounted in the carrier and connecting the opposed gears; 105 and means to drive the gears.

In testimony whereof I affix my signature.
ARTHUR R. COLLEY.
